(57) **CLAIM**

The ornamental design for a waist pouch, as shown and described.

DESCRIPTION

FIG. 1 is a front view of a waist pouch showing our new design;

FIG. 2 is a top view thereof;

FIG. 3 is a bottom view thereof;

FIG. 4 is a rear view thereof;

FIG. 5 is a left side view thereof;

FIG. 6 is a right side view thereof;

FIG. 7 is a front and top perspective view thereof; and,

FIG. 8 is a front and bottom perspective view thereof.

The strap is shown broken away in FIGS. 1–4 and FIGS. 7–8 to indicate indeterminate length.

The broken lines showing the buckles in FIGS. 1–8, belt slides in FIGS. 1–5 and 7–8, logo tag in FIGS. 1, 3 and 5–8, zipper in FIGS. 1, 3 and 5–8, and zipper slider in FIGS. 1–3 and 6–8, is for illustrative purposes only and forms no part of the claimed design.

The article in which the present design is embodied is a pouch with integrated belt, the pouch having a pleat that extends up inside from the bottom.
